MAGNETIC FLUID VARIABLE TORQUE WRENCH

Gorman R. Nelson, Sioux Falls, S. Dak.

Application January 8, 1954, Serial No. 402,865

5 Claims. (Cl. 81—52.4)

My invention relates to a torque wrench.

An object of my invention is to provide a torque wrench which will apply torque to a nut or other similar device by means of a suitable driving motor, and whereby a certain member using a magnetic fluid arrangement is interposed between the motor and the wrench unit itself to cause slippage when the nut is tightened to a pre-determined torque.

A further object of my invention is to provide a gearing arrangement in association with the wrench for increasing the torque at the wrench end.

A further object of my invention is to provide a certain sealing device which will allow the escape of heated gases developed in the magnetic fluid portion of the device, and yet will not allow the escape of the magnetic fluid itself, and which device will automatically re-seal the unit after the hot gases have escaped.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation of the torque wrench with the magnetic fluid drive portion as well as the gear drive portion being shown in cross section.

Figure 2 is a sectional view taken along the lines 2—2 of Figure 1, and

Figure 3 is a schematic view of the electrical circuit.

My invention contemplates the provision of a torque wrench in which the principle of the magnetic fluid drive is employed, so that after the wrench performs the operation of tightening the nut to a pre-set torque, the wrench portion will cease its rotation without affecting the driving motor, and contemplates principally the further provision of an arrangement for increasing the torque to the nut engaging portion of the device, and also the provision of an automatic sealing device which will provide for the escape of heated gases developed by the unit, and with an instant re-sealing of the unit when the device is at rest.

The present application is a continuation in part of my further application relating to Magnetic Fluid Variable Torque Wrenches, Serial No. 244,956, filed September 4, 1951, and relates to certain members thereon.

I have used the character 10 to designate a non-magnetic casing including the forward end portion 11, in which is secured the bearing member 12, which bearing member receives the shaft 13 including the squared portion 14 for engagement with the socket 15, which socket is to be used for tightening the nut, and suitably attached at 16 to the casing 10 is the non-magnetic handle 17.

Attached to the inner end of the shaft 13 is an enlarged gear 18 which meshes with a substantially smaller gear 19, the gear 19 being attached to a shaft 20 which is journaled within the bearing 21, the shaft 20 extending into the non-magnetic shaft portion 22, this shaft being engaged by means of a suitable sealing ring 23. The shaft 22 is journaled in the bearing 24 which is secured within the magnetic hub 25, which extends into the disk portion 26, the portion 26 being threadably attached at

2

27 to a further magnetic cylindrical member 28 which is integrally formed with the further disk member 29 which member 29 is secured as at 30 to the non-magnetic shaft 31 of a suitable air motor 32 which can be threadably engaged at 33 with the adapter member 34 which is non-magnetic and is secured at 35 to the casing 10.

Suitably secured to the member 29 is a further magnetic member 36 and positioned between the member 29 and 36 is an electro-magnetic coil 37. Attached to the periphery of the member 36 is a non-magnetic ring 38 to which is secured the inner spacers 39, and secured between the spacers 39 are the annular flat disks 40 which extend inwardly and are spaced from the inner spacers 41 which are secured to the extension 42 of the shaft 22, and attached between the spacers 41 are the further annular flat disks 43 which are correspondingly carried by the shaft 42, it being noted that the various disks 40 and 43 are spaced a slight distance apart. A nut 44 is threadably engaged with the shaft portion 42 to secure this assembly, and the casing provided between the member 26 and the member 36 is filled substantially to the level 45 with a magnetic fluid which magnetic fluid is preferably composed of oil having finely divided magnetic particles such as iron, suspended therein. The member 36 includes an extending hub portion 46 having the cavity 47 in which cavity is placed an elastic neoprene disk 48 having the transverse slit 49 therein, the disk 48 being secured by means of the ring 50.

Attached to the member 29 is a disk 51 which is made of a suitable non-conducting material in which member 51 are secured the annular conducting rings 52 which contact the brushes 53 and 54, these brushes being connected by means of suitable leads shown to a twin lead 55 which passes to a voltage control box such as a variable transformer 56 (see Figure 3), the lead to the brush 54 passing to a contact 57 which is adapted to contact the further contact 58 when the lever 59 is pulled by means of the finger grip portion 60, the various brushes, contacts, etc., being suitably insulated.

The air motor 32 includes the handle 61 secured thereto, both handles 17 and 61 being used when the tool is employed for tightening nuts and the like, it being understood that the handle 17 for instance can be placed at any position desired.

In using the device, the air motor 32 will rotate constantly, thereby driving the member 29, the member 51, as well as the portions 28, 26 and 25, and the flat annular disks 40. When the member 60 is pulled by the operator, contact will be established between the contact members 57 and 58 which will correspondingly energize the coil 37 which will energize the magnetic circuit which will reside in the various members 29, 28 and 25, the magnetic flux which passes across and between the portions 36 and 26 also passing through the disks 40 and 43, which magnetic flux passing also through the magnetic fluid will cause a positive magnetic binding attraction through the fluid and the disks, so that as a result, the rotation of the members 28 etc., will thereby cause the disks 43 to rotate, thereby rotating the shaft portions 42 and 22 which in turn will rotate the small gear 19, to thereby rotate the larger gear 18 and supplying torque to the shaft 13 for rotating the nut engaging member 15. As soon as the nut is tightened to a pre-set torque, slippage will occur between the disks and fluid, so that the motor 32 can still rotate without injury. The pre-set torque can be determined by regulating the voltage, and it will also be noted that the torque is multiplied through the gear arrangement at a diminished speed.

I have found that the magnetic fluid during the rapid rotation and slippage of the disks, will become heated to a degree wherein gases will form, and without the use of

the neoprene disk 48, these gases would escape past the sealing member 23 and into the bearings etc., causing harmful effects. However, by means of the slit 49 in the disk 48, during operation these gases upon expanding will force through the slit 49 which will open slightly to permit escape thereof, thereby relieving the pressure on the sealing member 23, and when the unit is not operating, the resilient nature of the neoprene member will cause the slit to close tightly again preventing waste of the magnetic fluid. During rotation of the tool, the magnetic fluid will be centrifugally urged outwardly thereby filling the entire annular space, forming a hollow pocket as indicated by the dotted line character 62 and the fluid will then be spaced from the neoprene disk, and it should be specifically understood that disks of other material could be used as well, neoprene being preferred since it is oil resistant.

It will now be noted that I have provided the various advantages mentioned in the objects of my invention with other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A variable torque wrench comprising a driven shaft, a casing attached to said shaft, said casing containing a magnetic fluid therein, said casing further including magnetic portions, a further shaft rotatable in said casing, magnetic disks attached to said further shaft whereby rotation of said casing will cause a binding magnetic action between said magnetic casing portions and said disks to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, one end of said casing having an aperture therein, a resilient member secured across said aperture, said resilient member including a lengthened slit to provide means for causing escape of hot gases caused by the heat effects generated in said casing during rotation and slippage of said disks, and whereby said slit will re-seal said resilient member to retain said magnetic fluid when said wrench is in an inoperative condition.

2. A variable torque wrench comprising a driven shaft, a casing attached to said shaft, said casing containing a magnetic fluid therein, said casing further including magnetic portions, a further shaft rotatable in said casing, magnetic disks attached to said further shaft whereby rotation of said casing will cause a binding magnetic action between said magnetic casing portions and said disks to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, one end of said casing having an aperture therein, a resilient member secured across said aperture, said resilient member including a lengthened slit to provide means for causing escape of hot gases caused by the heat effects generated in said casing during rotation and slippage of said disks, and whereby said slit will re-seal said resilient member to retain said magnetic fluid when said wrench is in an inoperative condition, said aperture and said resilient disk being positioned substantially along the longitudinal axis of said further shaft.

3. A variable torque wrench comprising a driven shaft, a casing attached to said shaft, said casing containing a magnetic fluid therein, said casing further including magnetic portions, a further shaft rotatable in said casing,

magnetic disks attached to said further shaft whereby rotation of said casing will cause a binding magnetic action between said magnetic casing portions and said disks to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, one end of said casing having an aperture therein, a resilient member secured across said aperture, said resilient member including a lengthened slit to provide means for causing escape of hot gases caused by the heat effects generated in said casing during rotation and slippage of said disks, and whereby said slit will re-seal said resilient member to retain said magnetic fluid when said wrench is in an inoperative condition, said aperture and said resilient disk being positioned substantially along the longitudinal axis of said further shaft, an outer stationary casing enclosing said casing, means for increasing the torque of said further shaft including a small gear attached to said further shaft, a larger gear meshing with said small gear, a still further shaft attached to said larger gear, a nut engaging member attached to said still further shaft.

4. A variable torque wrench comprising a driven shaft, a casing attached to said shaft, said casing containing a magnetic fluid therein, said casing further including magnetic portions, a further shaft rotatable in said casing, annular members attached to said further shaft whereby rotation of said casing will cause a binding magnetic action between said magnetic casing portions and said annular members to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, one end of said casing having an aperture therein, a resilient member secured across said aperture, said resilient member including a lengthened slit to provide means for causing escape of hot gases caused by the heat effects generated in said casing during rotation and slippage of said annular members, and whereby said slit will re-seal said resilient member to retain said magnetic fluid when said wrench is in an inoperative condition.

5. A variable torque wrench comprising a driven shaft, a casing attached to said shaft, said casing containing a magnetic fluid therein, said casing further including magnetic portions, a further shaft rotatable in said casing, magnetic disks attached to said further shaft whereby rotation of said casing will cause a binding magnetic action between said magnetic casing portions and said disks to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, one end of said casing having an aperture therein, a resilient member secured across said aperture, said resilient member including a lengthened slit to provide means for causing escape of hot gases caused by the heat effects generated in said casing during rotation and slippage of said disks, and whereby said slit will re-seal said resilient member to retain said magnetic fluid when said wrench is in an inoperative condition.

6. A variable torque wrench comprising a driven shaft, a casing attached to said shaft, said casing containing a magnetic fluid therein, said casing further including magnetic portions, a further shaft rotatable in said casing, magnetic disks attached to said further shaft whereby rotation of said casing will cause a binding magnetic action between said magnetic casing portions and said disks to thereby rotate said further shaft, means for electrically energizing said casing magnetic portions including a coil wound in said casing, means for electrically energizing said coil including an electric circuit passing thereto, a switch in said circuit whereby the magnetic circuit can be broken when desired, an outer stationary casing enclosing said casing, means for increasing the torque of said further shaft including a small gear attached to said further shaft, a larger gear meshing with said small gear, a still further shaft attached to said larger gear, a nut-engaging member attached to said still further shaft.
